UNITED STATES PATENT OFFICE.

KIRBY FITZPATRICK, OF HARTSVILLE, TENNESSEE.

STEAM-ENGINE.

SPECIFICATION forming part of Letters Patent No. 695,451, dated March 18, 1902.

Application filed March 8, 1901. Serial No. 50,379. (No model.)

To all whom it may concern:

Be it known that I, KIRBY FITZPATRICK, a citizen of the United States, residing at Harts-ville, in the county of Trousdale and State of Tennessee, have invented a new and useful 5 Steam-Engine, of which the following is a specification.

This invention relates to steam-engines; and it has for its object to provide a construction wherein the parts may be adjusted for the cylinders to feed and exhaust in multiple for single expansion or may be adjusted for a central cylinder to be brought into communication with the end cylinders of a triple series of cylinders to secure a second expansion of steam, further objects and advantages of the invention relating to various details being fully set forth in the following specification.

20 In the drawings forming a portion of this specification, and in which like numerals of reference indicate similar parts in the several views, Figure 1 is a sectional view taken longitudinally of the cylinder of the engine and 25 showing the valve mechanisms and ports in diagram. Fig. 2 is a side elevation of the cylinder with parts of the exterior mechanism in elevation. Fig. 3 is a view similar to Fig. 1 and showing the pistons in their opposite 30 positions. Fig. 4 is a sectional view showing the arrangement of the valve for the piston. Figs. 5 and 6 are detail perspective views of the valves for the pistons and partitions. Fig. 35 7 is a view similar to Fig. 1 and showing the parts shifted for single-expansion work. Fig. 8 is a detail perspective view of the shifting link.

Referring now to the drawings, there is shown a cylinder 5, which is divided into three 40 expansion-chambers 6, 7, and 8 by means of a transverse partition 9 and a second partition 10, and in these three chambers are disposed three pistons 11, 12, and 13, one in each chamber, and all three connected to a common 45 piston-rod 14, which may be connected in any suitable manner with a driven shaft. (Not shown.) Two chests 15 and 16 are provided, the former being for feed-steam and the latter for exhaust-steam. With the chest 15 are connected 50 two groups of ports of three each, one group comprising ports 17, 18, and 19 and the other group comprising the ports 20, 21, and

22. The ports 17, 18, and 19 are connected with the left-hand ends of the several expansion-chambers, and the ports 20, 21, and 22 55 are connected with the right-hand ends of the cylinders or expansion-chambers, and for each group of ports there is provided a slide-valve 23 and 24, respectively, connected with a common shift-rod 25, which when operated moves 60 the valves to cover and uncover the groups of ports interchangeably. Two groups, each of three ports, lead from the expansion-chambers to the chest 16, the ports 26, 27, and 28 of one group being connected with the left-hand 65 ends of the expansion-chambers, while the ports 29, 30, and 31 of the other group are connected with the right-hand ends of the chambers, these ports being exhaust-ports. The two groups of ports have slide-valves 32 and 70 33 for movement to cover the groups interchangeably, and these valves are connected with a valve-rod 34. The rods 25 and 34 are connected at their ends with parallel side pieces 35 and 36 to form a rectangular frame, 75 and these side pieces have rods 37 and 38, which project through the ends of the chambers 6 and 8 and into the paths of movement of the pistons 11 and 13, respectively, so that the frame, including the rods 25 and 34, will 80 be reciprocated from the pistons. With this construction it will be seen that if steam be supplied to the chest 15 the pistons will be reciprocated in their expansion-chambers, the cylinders operating in multiple. 85

When the engine is to be used as a double-expansion engine, all of the feed-ports, with the exception of the ports 19 and 20, leading to the inner ends of the chambers 6 and 8, are cut off, while the exhaust-ports 28 and 90 29, leading from the inner ends of these chambers 6 and 8, are also cut off. For thus cutting off the ports they are provided with rotary valves 39 and 40, having cranks connected with shift-rods 41 and 42, which in 95 turn are connected with a hand-lever 43 for actuation thereby. In the double-expansion arrangement steam is permitted to enter the chamber 8 through port 19 behind the piston 13, moving the piston-rod and all three pistons to the right. After the pistons have moved to the right valves are opened through the piston 13 and the partition 10, and the piston 12 being then close up to the partition 100

10 the steam in chamber 8 further expands and runs through the valved opening in partition 10 and acting against the adjacent face of the piston 12 moves the latter to the left. 5 When steam is thus acting on piston 12 to move it to the left, port 20 is uncovered and steam enters between piston 11 and partition 9 and forces piston 11 to the left. When the movement to the left has then terminated, 10 cylinders 7 and 8 exhaust from their right-hand ends and valves in piston 11 and partition 9 open to permit of expansion of steam into chamber 7 behind piston 12 and against the left-hand end of the cylinder to move the 15 piston to the right, a new charge of steam being at the same time admitted to chamber 8 against piston 13.

The valves for the two pistons 11 and 13 and the two partitions 9 and 10 consist of two 20 rods 40 and 41, passed into the opposite ends of the cylinder and projecting with their inner or adjacent ends into the chamber 7, said rods being cylindrical and lying in arcuate recesses in the inner face of the cylinder. These 25 two valves have cut-away portions 42, and when the valves are in one position their rounded sides project into the cylinder and completely fill arcuate openings in the partitions and the peripheries of the pistons 11 and 30 13, so that there can be no passage of steam from one side to the other of the partitions and pistons, and when the valves are rotated to their opposite positions their rounded sides will lie in the recesses or channels in the inner 35 face of the cylinder, while their cut-away portions will be turned inwardly, so that the openings in the pistons and partitions will not be closed and there will be a free passage of steam. As the second expansion occurs 40 alternately at opposite ends of the cylinder, the valves must be rocked so as close and open the passages or ports in partitions and pistons correspondingly, and for this purpose the following mechanism is provided:

45 Pivoted links 45 and 46 are mounted upon suitable supports and are adapted to be rocked from the rod 34, with which they are connected by means of collars 35' and 36', mounted upon the rod, and which collars lie 50 between pins 47 on the rod 34 to permit of some lost motion of the rod with respect to the collars, these pins being adapted to strike their respective collars alternately, so as to move them and rock the links. The links 55 have each a block 49 mounted therein for sliding movement to and from a position to lie over the pivot of the link, and this block of each link is connected, by means of a pitman or connecting-rod 50, with a laterally-projecting arm 51 on the protruding end of the adjacent valve, so that as the link is rocked the valve will be rocked. When the engine is used as a single-expansion engine, these 60 valves must of course remain closed, and for this purpose the blocks 49 are connected with hand-lever 43, as shown, so that when the feed and exhaust ports are cut into operation

the blocks 49 will be slid along the links to their inactive positions.

With this construction it will be seen that 70 there is a saving over the usual compound engine wherein the steam is transferred from one cylinder to another, owing to the absence of friction incident to transference of steam and other causes incident thereto. In the 75 present construction the valved piston is, in effect, taken away, as also the valved partition, and the steam expands then between the middle piston and the head of the cylinder.

An additional advantage in the present construction is that when using as a compound engine or as a single-expansion engine the number of cylinders may be cut down in case of a break.

What is claimed is—

1. An engine comprising a cylinder having partitions and resultant end chambers and an intermediate expansion-chamber, a piston in each expansion-chamber and having a common piston-rod, inlet-ports for supplying 90 steam to the inner ends of the outer chambers, outlet-ports for exhausting from the outer ends of the outer chambers and both ends of the inner chamber, and valved ports for communicating the expansion ends of the 95 outer chambers alternately with the adjacent ends of the inner chamber.

2. An engine comprising a cylinder having partitions and resultant end chambers and an intermediate expansion-chamber, a piston in each expansion-chamber and having a common piston-rod, means for supplying steam alternately to the inner ends of the end chambers, ports through the partitions and the pistons in the end cylinders, valves for opening 105 and closing the ports in the pistons and their adjacent partitions, to permit of access of steam to opposite sides of the inner piston alternately, and exhaust-ports for the chambers.

3. An engine comprising a cylinder including a series of expansion-chambers having each a piston and having a common rod, inlet and outlet ports for each end of each chamber, valved ports through the partitions between the chambers, and means for alternately opening all feed and exhaust ports to operation, and for closing certain of said ports simultaneously with the opening of the ports in the pistons and partitions.

4. An engine comprising a cylinder having end chambers and an intermediate expansion-chamber, a piston in each chamber having a common piston-rod, inlet and exhaust ports for the chambers, valve mechanism for connecting the exhaust-ports of the outer cylinders interchangeably with the ends of the intermediate chamber, a common feed-pipe, a common exhaust-pipe, and valve mechanism for connecting the cylinders in multiple between the feed and exhaust pipes.

5. A multiple-cylinder engine adapted for use as a direct-acting or as a compound engine and comprising in combination, three

cylinders arranged in tandem, and having separating-partitions provided with valved ports, pistons in each of said cylinders, a piston-rod common to all of said pistons, the end 5 pistons having valved ports to permit the passage of steam therethrough, means for opening and closing the valved ports of the partitions and pistons, inlet and exhaust ports leading to all of said cylinders, and means 10 for closing certain of said ports to direct the

exhaust of the end cylinders to the intermediate cylinder when the engine is changed from a direct-acting to a compound.

In testimony that I claim the foregoing as my own I have hereto affixed my signature in 15 the presence of two witnesses.

KIRBY FITZPATRICK.
